BUTTON AND PROCESS OF MAKING SAME

Neil O. Broderson, Rochester, N. Y., assignor to
 Rochester Button Company, Rochester, N. Y.,
 a corporation of New York

Application October 10, 1938, Serial No. 234,331

17 Claims. (Cl. 41—10)

This invention relates to an improved button and process of making the same.

An object of this invention is the production from a plastic substance of a button possessing the appearance of natural hoof, horn, shell, or other similar material.

Another object of this invention is the preparation of such a button from synthetic raw materials at a cost considerably lower than if natural materials were employed.

Another object of this invention is to provide a simplified process for the manufacture of buttons, whereby useful and decorative natural appearing buttons result.

Another object of this invention is to provide a button not only simulating one made from natural horn in tone and hue, but also in grain structure.

Another object of this invention is to provide a button comprising a body made of two or more layers of plastic substance bonded together, the contacting surfaces of the layers being corrugated or otherwise roughened to obtain good bonding therebetween by providing interpenetrating surfaces at the interfaces.

Still further objects of the invention will be apparent from the following description.

The present invention includes a process of making buttons wherein two or more different colored layers of plastic substance are bonded together in parallel relationship so as to form a unitary sheet, from which button blanks are stamped or cut. A blank is then worked into a button by the usual button-cutting methods, so that the plane of the finished button makes an acute angle with the interfacial planes between the layers of said blank. The front surface of the finished button may or may not intersect one or more of the aforementioned interfacial planes.

In case the button is so cut that its front surface intersects one or more of the interfacial planes, portions of different colored layers will be exposed in this front surface, thereby giving the finished article the appearance of natural horn or other natural materials such as hoof or shell, depending upon the color and texture of the independent layers.

However, if the front surface of the button intersects none of the interfacial planes but lies wholly within one layer, and this layer of plastic substance is somewhat translucent and lighter in color than the layer directly behind it, the varying thickness of the first layer, due to the interfacial planes being maintained in angular relationship with the plane of the button, will permit the color

of the layer behind it to show through with varying intensity depending upon the thickness of the covering layer, thereby giving the button an artistic appearance like that of natural horn.

5 The invention will be more particularly described for the purpose of illustration as applied to the production of casein buttons and with reference to the accompanying drawing in which:

Fig. 1 is a perspective view of a laminated plastic sheet from which a number of button blanks have been cut;

Fig. 2 is a perspective view of one of the blanks;

Fig. 3 is a cross-sectional view of a blank, showing, in broken lines, the position of a potential finished button;

Fig. 4 is a plan view of one type of button cut according to Fig. 3;

Fig. 5 is a cross-sectional view of a blank, showing, in broken lines, another position of a potential button;

Fig. 6 is a plan view of the button cut according to Fig. 5;

Fig. 7 is a cross-sectional view of another type blank according to the present invention, showing, in broken lines, the position of a potential button;

Fig. 8 is a plan view of a button cut according to Fig. 7;

Fig. 9 is a cross-sectional view of a blank similar to the blank of Fig. 7, but showing, in broken lines, another position of a potential button;

Fig. 10 is a plan view of a button cut according to Fig. 9;

Fig. 11 is a fragmentary perspective view of a portion of a laminated sheet of plastic material having a corrugated interface from which buttons may be made in accordance with this invention; and

Fig. 12 is a plan view of a button made from a sheet of plastic substance like that shown in Fig. 11.

In the drawing, like numbers refer to corresponding parts.

In forming the sheet stock from which the buttons are to be made, two layers of uncured casein are laid up, as 1 and 2 in Fig. 1 of the drawing, the separate sheets being of contrasting colors or tones. The two layers are then pressed to form a firm unitary sheet of such thickness that the cured stock will be of the desired gauge for the button blanks.

The sheet so prepared is next hardened in known manner, as by curing in formaldehyde solution. Button blanks, in the shape of discs of the required diameter, are then stamped or

cut from the hardened sheet. One of these discs is shown in Fig. 2.

Greater mechanical strength is obtained at the joint between the laminae and enhanced decorative effect is achieved in the finished button, if the layers of plastic substance are corrugated or otherwise roughened at their interfaces. For example, a sheet may be prepared, as shown in Fig. 11, by partially consolidating uncured casein to form a layer 6 having a corrugated surface 7. According to one method of accomplishing this result, a metal plate having engraved on its surface the counterpart of the roughened surface desired on the layer, is pressed upon a preformed plane layer of casein lying upon a smooth bed plate, the conditions of time, temperature and pressure being so regulated that only partial consolidation of the casein results. The corrugated pressure plate is removed, a second different-colored preformed but plane layer of casein 8 is positioned upon the corrugated surface of the partially consolidated layer of casein, and a plane and smooth pressure plate is brought down upon the top surface of the upper layer with very great pressure and at a temperature high enough to cause the upper layer to flow into the corrugations of the lower layer and interlock therewith and to completely unify the laminated structure to form a unitary coherent sheet having an irregular line of juncture between the component layers.

A plurality of layers of plastic may be joined in like manner, the interfacial joints between the layers being corrugated. Other methods of roughening and bonding the layers of plastic material may be employed within the scope of this invention.

Referring to Fig. 3 of the drawing, in which the broken lines delineate and bound that portion of the blank which will constitute the finished button, it will be seen that the plane of the button lies at an acute angle to the interfacial plane between the laminae of the blank. Further, it will be apparent that the front surface of the finished button will intersect this interfacial plane. This line of intersection in the front surface of the finished button will divide it into two areas of different colors corresponding to the colors of the individual layers 1, and 2. It is this variegated surface effect shown in Fig. 4, which gives a desirable ornamental appearance similar to that of natural horn or hoof.

In order to obtain this effect, the portions of the blank outside the broken lines in Fig. 3 must be cut away. This may be accomplished in several ways. One method of so doing is to mount the blank in the chuck of a button lathe so that the angle between the interfacial plane of said blank and the plane of rotation of the chuck is equal to that acute angle desired between the aforementioned interfacial plane and the plane of the finished button, and then to turn down the face of the blank, with the usual straight cutting tool, until portions of the under layer are exposed in the surface of the button. After this facing operation is complete, the half-turned blank may be reversed in the chuck, with the plane of the button and the plane of rotation of the chuck in parallel relationship, and the back of the button machined to the correct contour with respect to the face. Drilling the thread holes, and subsequent finishing operations may be done in any convenient manner.

The tools and apparatus for machining buttons are well known, and other equivalent methods of

machining a laminated blank according to this invention will be apparent to those skilled in the button art. For example, instead of being turned, the blank may be held stationary, and a rotating cutter applied to shape the surface at an angle to the interfacial plane.

Fig. 5 illustrates an alternative position of a potential button within a blank comprising two layers. Here the front surface of the button lies entirely in one layer of the blank, but the interfacial plane between the layers is disposed at an acute angle to the plane of the button. The plastic substance contained in the face of the finished button is of lighter color than the backing layer, and sufficiently translucent that the backing layer is partially visible therethrough. This results in a variegated surface effect, as shown in Fig. 6.

Although the invention has been illustrated with reference to a button blank formed of two parallel layers, it is obvious that a blank of more than two parallel layers might be used to produce an enhanced decorative effect. Fig. 7 shows a blank composed of three layers, and indicates in broken lines the relative position of a potential button, the front surface of which intersects both interfacial planes. Fig. 8 is a plan view of the button cut from the blank of Fig. 7, in which the three layers 3, 4 and 5 of the blank appear on the face of the button.

Fig. 9 shows another potential button in a three-layered blank in such a position that the front surface of the button cuts one of the interfacial planes but not the other, although the finished button will be composed of three layers and will appear in plan view as shown in Fig. 10, layers 3 and 4 appearing on the face of the button and layer 5 being partially visible through a portion of layer 4.

The specific examples of buttons cut according to this invention thus far described have been limited to buttons having smooth interfacial planes. However, if the interfacial planes between the layers of the button blank are roughened, as hereinbefore explained, buttons may be made from such blanks in the same manner as those already discussed, and the resulting buttons are not only stronger but also may have a more attractive appearance than those having smooth interfacial planes.

One such button is shown in Fig. 12, and a natural appearing grain similar to that of horn is evident along the line 9-9, where the inter-laminal plane or joint intersects the face of the button. The corrugations, where they are seen in side view on the finished button, also lend a natural appearance to the article.

Throughout the specification and claims the word "roughened" is used in its broadest sense to describe a surface condition which may be corrugated, wavy, crinkled, granular or the like.

The invention is not limited to casein as the plastic substance from which the stock is made. Any plastic substance may be used provided it can be formed into layers, and the layers bonded together to form a unitary sheet, from which blanks may be cut to be machined into buttons. For example, horn flour might be substituted for casein, and the laminated sheet hardened and unified by subjecting it to heat and pressure. Or sheets of heat-hardenable urea-formaldehyde condensation product may be prepared in like manner. The laminated stock sheet may also be cast from a casting type resin such as a phenol-formaldehyde casting resin.

Fillers or pigments may be added to the casein or other plastic substances to give unique ornamental effects, or to modify the physical characteristics of the button. The terms "color" and "colored" in the specification and claims are used in their broadest sense to indicate variations in appearance due to differences in hue, tone, transparency, grain, iridescence and the like.

This application is a continuation-in-part of my prior application Serial Number 183,538, filed January 5, 1938.

I claim:

1. Process of making a button which comprises unifying a plurality of different colored parallel layers of plastic substance to form a button blank, and cutting said button blank at an acute angle to the interfacial planes between the layers of said blank to form a button, the plane of which is at an acute angle to said interfacial planes. 15

2. Process of making a button which comprises cutting a laminated varicolored blank at an acute angle to the planes between the laminae whereby to form a laminar button, the plane of which makes an acute angle with the interfacial planes between the laminae thereof.

3. Process of making a button which comprises unifying a plurality of different colored, parallel layers of plastic substance to form a sheet of machinable hardness, cutting therefrom a button blank, and machining said button blank at an acute angle to the interfacial planes between the layers of said blank to form a button, the plane of which is at an acute angle to said interfacial planes.

4. Process of making a button which comprises unifying two different colored layers of plastic substance to form a sheet of machinable hardness, cutting therefrom a button blank, and machining said button blank at an acute angle to the interfacial plane between the layers of said blank to form a button, the plane of which is at an acute angle to said interfacial plane.

5. Process of making a button which comprises unifying a plurality of different colored parallel layers of plastic substance to form a sheet of machinable hardness, cutting therefrom a button blank, and machining said button blank at an acute angle to the interfacial planes between the layers of said blank to form a button, the plane of which is at an acute angle to said interfacial planes and the front surface of which intersects at least one of the interfacial planes.

6. Process of making a button which comprises unifying three different colored parallel layers of plastic substance to form a sheet of machinable hardness, cutting therefrom a button blank, and machining said button blank at an acute angle to the interfacial planes between the layers of said blank to form a button, the plane of which is at an acute angle to said interfacial planes and the front surface of which intersects only one of said interfacial planes.

7. Process of making a button which comprises unifying two different colored layers of plastic substance to form a sheet of machinable hardness, cutting therefrom a button blank, and machining said button blank at an acute angle to the interfacial plane between the layers of said blank to form a button, the plane of which is at an acute angle to said interfacial plane and the front surface of which intersects the interfacial plane.

8. Process of making a button which comprises unifying two different colored layers of plastic substance to form a sheet of machinable hardness, cutting therefrom a button blank, and machining said button blank at an acute angle to the interfacial plane between the layers of said blank to form a button, the plane of which is at an acute angle to said interfacial plane and the front surface of which does not intersect the interfacial plane.

9. A button comprising a plurality of different colored parallel layers of plastic substance bonded together, the interfacial planes between said layers being disposed at an acute angle to the plane of the button.

10. A button comprising two different colored layers of plastic substance bonded together, the interfacial plane between said layers being disposed at an acute angle to the plane of the button.

20 11. A button comprising three different colored parallel layers of plastic substance bonded together, the interfacial planes between said layers being disposed at an acute angle to the plane of the button, and the front surface of the button intersecting one of the interfacial planes but not the other.

12. A button comprising a plurality of different colored parallel layers of plastic substance bonded together, the interfacial planes between 30 said layers being disposed at an acute angle to the plane of the button and the front surface of the button intersecting at least one of the interfacial planes.

13. A button comprising two different colored layers of plastic substance bonded together, the interfacial plane between said layers being disposed at an acute angle to the plane of the button and the front surface of the button intersecting the said interfacial plane.

40 14. A button comprising two different colored layers of plastic substance bonded together, the interfacial plane between said layers being disposed at an acute angle to the plane of the button and the front surface of the button not intersecting the interfacial plane.

45 15. Process of making a button which comprises unifying a plurality of different colored parallel layers of plastic substance having at least one roughened surface to form a sheet of machinable hardness, cutting therefrom a button blank, and machining said button blank at an acute angle to the interfacial planes between the layers of said blank to form a button, the plane of which is at an acute angle to said interfacial planes.

55 16. A button comprising a plurality of different colored parallel layers of plastic substance bonded together, said layers having interpenetrating interfacial surfaces, and the interfacial planes between said layers being disposed at an acute angle to the plane of the button.

60 17. A button comprising a plurality of different colored parallel layers of plastic substance bonded together, said layers having interpenetrating interfacial surfaces, and the interfacial planes between said layers being disposed at an acute angle to the plane of the button and the front surface of the button intersecting at least one of the interfacial planes.
